United States Patent

Des. 238,645

Patented Feb. 3, 1976

238,645

RACK

William M. Becker, 5915 Onondaga Road,
Bethesda, Md. 20016

Filed Sept. 27, 1974, Ser. No. 509,933

Term of patent 14 years

Int. Cl. D6—04

U.S. Cl. D6—184

FIG. 2.

FIG. 3.

FIG. 1.

FIG. 4.

FIG. 5.

FIG. 6.

FIG. 1 is a front elevational view of a rack showing my new design;

FIG. 2 is a top plan view thereof;

FIG. 3 is an elevational view of one side of my rack, looking at it from the left side of FIG. 1.

FIG. 4 is an elevational view of the side of my rack opposite the side shown in FIG. 3.

FIG. 5 is a bottom plan view of my rack.

FIG. 6 is an elevational view showing the back of my rack.

I claim:

The ornamental design for a rack, as shown.
